United States Patent Office

Des. 219,142
Patented Nov. 10, 1970

219,142

CAMPER TOP

William A. Ritter, 1030 Arroyo St.,
San Fernando, Calif. 91340

Filed July 25, 1969, Ser. No. 18,399

Term of patent 7 years

Int. Cl. D12—14

U.S. Cl. D14—27

FIG. 1

FIG. 2

FIG. 3

FIG. 4

FIG. 5

FIG. 1 is a side elevational view of a camper top showing my new design;

FIG. 2 is a top plan view thereof;

FIG. 3 is a bottom plan view thereof;

FIG. 4 is a front elevational view thereof; and

FIG. 5 is a rear elevational view thereof.

I claim:

The ornamental design for a camper top, substantially as shown.
